K. H. PERKINS

NEEDLE OR STYLE FOR GRAMOPHONES AND LIKE MACHINES

Filed July 13, 1922

FIG. 1

FIG. 3

FIG. 2

Inventor.

Kenneth Harold Perkins

By Glenn S. Noble
-Atty

UNITED STATES PATENT OFFICE.

KENNETH HAROLD PERKINS, OF REDDITCH, ENGLAND.

NEEDLE OR STYLE FOR GRAMOPHONES AND LIKE MACHINES.

Application filed July 13, 1922. Serial No. 574,601.

To all whom it may concern:

Be it known that I, KENNETH HAROLD PERKINS, subject of the King of Great Britain, and residing at "The Cedars," Astwood Bank, Redditch, England, have invented certain new and useful Improvements in Needles or Styles for Gramophones and like Machines, of which the following is a specification.

10 This invention refers to an improved needle or style for gramophones and the like, and has for its object to provide a single needle or style bearing two blades or points of different lengths, so that the same needle 15 may be employed for producing either "loud" or "soft" tones as required.

By this means there is a considerable saving in manufacturing expense as only one set of discs is required while the life of 20 each needle in use is considerably prolonged.

My invention essentially comprises a needle or style for a gramophone or like machine in which a stem or shank carries a pair of flattened blades set at an angle thereto, the blades being of different lengths, and preferably of different thickness, and terminating in points which lie on opposite sides of the axial line of the stem or shank.

By turning the needle through a half 30 revolution in the holder on the reproducer either point may be caused to engage the sound record or groove on the record disc, and flats are preferably formed on opposite sides of the stem or shank, the flats being 35 adapted to be engaged by the clamping screw which secures the needle in the holder to ensure the needle being correctly placed therein.

Any other suitable means may be provided 40 for this purpose, as for example, the stem or shank or the needle may be of square or other angular cross-section.

The blades are preferably of a thickness substantially equal to the width of the sound 45 record or "groove" on the record disc so that they may be a working fit therein and do not foul the sides of the groove. The needle may thus be used repeatedly without appreciable wear either of the needle or record, 50 and the objectionable sibilant noise caused by the contact of a round pointed needle with the sides of the groove is eliminated.

One preferred embodiment of my inven-

tion is illustrated in the accompanying drawings in which—

55 Figure 1, is a side elevation on an enlarged scale of the lower portion of a needle.

Figure 2, is an end elevation of Fig. 1.

Figure 3, is a sectional plan on the lines 3—3 of Fig. 1.

In the drawings *a* is the cylindrical stem or shank of the needle having flattened portions *b*, *c*, on opposite sides of its periphery, and *d*, *e*, are the flattened blades. The needle is preferably made from steel wire or like 65 material, and the flattened blades may be formed by stamping, pressing, grinding, or milling.

The shaping of the blades may be effected by trimming or shearing either in the same 70 tools or in a subsequent operation, and the plane of the blades may coincide with the axis of the stem, or may coincide with one side face of the stem as shown in Fig. 2. The latter construction is preferred as a 75 better tone is obtained with a needle of this construction in use.

By turning the needle within the holder on the reproducer either of the blades or points *d*, *e*, may be caused to engage the 80 record disc, and as the point *e* is longer and more resilient than the point *d*, the point *e* will give a "soft" tone, while the point *d* will give a "loud" tone.

As is shown in Fig. 2, the blades are extremely thin in a direction at right angles to the sound record or "groove" on the record disc, their thickness being substantially equal to the width of the groove so that they may be a smooth working fit 90 therein.

If desired the blade *e* for soft tones may be made of slightly less thickness than the blade *d* to give greater resilience, convenient thicknesses of the two blades being, for example, five thousandths and eight thousandths of an inch respectively.

95 I claim:—

1. A needle or style for gramophones and the like comprising a shank part having a 100 pair of pointed blades at one end set at an angle thereto.

2. A needle or style for gramophones and the like, comprising a shank part having at one end a pair of flattened blades each set 105 at an angle to the shank, said blades being

of different lengths and terminating in points which lie on opposite sides of the axial line of the shank.

3. A needle or style for gramophones and the like, comprising a shank part, flats on opposite sides of said shank part, a flattened end to said shank part, said end being formed into two pointed blades of different lengths each set at an angle to the shank part.

4. A needle or style for gramophones and the like, comprising a shank part, means on said shank for enabling it to be secured in the needle holder of a machine in either of two positions, a pair of flattened blades at one end of the shank part, the plane of said

blades being approximately coincident with one side of the shank part, each of said blades terminating in a point and being set at an angle to the shank.

20

5. A needle or style for gramophones or the like comprising a shank with a flattened portion at one end formed into two pointed blades of different thicknesses.

6. A needle or style for gramophones or the like comprising a shank with a flattened end formed into two pointed blades of different lengths each set at an angle to the shank part.

25

In testimony whereof I affix my signature.

KENNETH HAROLD PERKINS.
